US00D981243S

(12) **United States Design Patent** (10) Patent No.: **US D981,243 S**
(45) Date of Patent: **** Mar. 21, 2023**

(54) **PERFUME DIFFUSER**

(71) Applicant: **GUERLAIN**, Paris (FR)

(72) Inventor: **Sana Haddad Marchon**, Levallois Perret (FR)

(73) Assignee: **GUERLAIN**, Paris (FR)

(**) Term: **15 Years**

(21) Appl. No.: **35/512,921**

(22) Filed: **Oct. 29, 2021**

(80) **Hague Agreement Data**

Int. Filing Date: **Oct. 29, 2021**

Int. Reg. No.: **DM/217139**

Int. Reg. Date: **Oct. 29, 2021**

Int. Reg. Pub. Date: **Nov. 12, 2021**

(30) **Foreign Application Priority Data**

May 4, 2021 (EM) 008529473-0002

(51) LOC (14) Cl. **07-01**

(52) U.S. Cl.

USPC **D9/560**

(58) **Field of Classification Search**

USPC D9/560, 574, 432, 452, 529, 544
CPC ... A45D 40/0068; A45D 40/00; A45D 33/006
